US0D1087189S

(12) **United States Design Patent** (10) **Patent No.:** **US D1,087,189 S**
(45) **Date of Patent:** **** Aug. 5, 2025**

(54) **CONROD FOR RECIPROCATING CUTTING TOOL**

(71) Applicant: **Arbortech Pty Ltd**, Malaga (AU)

(72) Inventors: **Benjamin Inkster**, Malaga (AU); **Glen Humphries**, Malaga (AU)

(73) Assignee: **Arbortech Pty Ltd.**, Malaga (AU)

(**) Term: **15 Years**

(21) Appl. No.: **29/903,739**

(22) Filed: **Sep. 27, 2023**

(30) **Foreign Application Priority Data**

Mar. 28, 2023 (AU) 202311785

(51) **LOC (15) Cl.** **15-09**

(52) **U.S. Cl.**

USPC **D15/138**; D15/139

(57) **CLAIM**

The ornamental design for a conrod for reciprocating cutting tool, as shown and described.

DESCRIPTION

FIG. 1 is a first isometric view of our new design of a conrod for reciprocating cutting tool thereof;

FIG. 2 is a second isometric view thereof;

FIG. 3 is a third isometric view thereof;

FIG. 4 is a fourth isometric view thereof;

FIG. 5 is a fifth isometric view thereof;

FIG. 6 is a sixth isometric view thereof;

FIG. 7 is a seventh isometric view thereof;

FIG. 8 is a eighth isometric view thereof;

FIG. 9 is a plan view thereof;

FIG. 10 is a bottom view thereof;

FIG. 11 is a first side elevation view thereof;

FIG. 12 is a second side elevation view thereof;

FIG. 13 is a front elevation view thereof;

FIG. 14 is a rear elevation view thereof; and,

FIG. 15 is an environmental view thereof.

1 Claim, 15 Drawing Sheets
